UNITED STATES PATENT OFFICE.

EDWARD W. SCOTT, OF ATTLEBOROUGH, MASSACHUSETTS, ASSIGNOR TO
THE WATSON & NEWELL COMPANY, INCORPORATED, OF SAME PLACE.

DESIGN FOR A HANDLE FOR SPOONS, &c.

SPECIFICATION forming part of Design No. 27,283, dated July 6, 1897.

Application filed May 25, 1897. Serial No. 638,166. Term of patent 14 years.

To all whom it may concern:

Be it known that I, EDWARD W. SCOTT, of Attleborough, in the county of Bristol and State of Massachusetts, have invented and 5 produced a new and original Design for the Handle of a Spoon, Fork, or Similar Article, of which the following is a specification, reference being had to the accompanying drawings, forming part thereof.

- 10 Figure 1 is a view of the obverse side of the handle, showing the same in connection with the bowl of a spoon in solid lines and with the tines of a fork in broken lines. Fig. 2 is a view of the reverse side of the same.
15 The leading features of my design consist in the bold raised bead extending around the margin of both sides of the handle and two inwardly-turned scrolls supporting a radial ornament within the marginal bead at the 20 upper end of both sides of the handle.

In the drawings, A indicates the bowl of the spoon, B the stem of the handle, and C, the upper end or blade of the handle; d, a bold convex bead of a width equal to about 25 one-third the width of the narrow part of the stem of the handle at e. These beads d terminate at the lower end of the handle in the scrolls f f. Within the beads d d and parallel therewith are the stems g g, terminating

at the upper end of the handle in the inwardly-turned scrolls h, inclosing the panels i i, convex on the obverse side of the handle and concave on the reverse side. 30

On the obverse side of the handle scrolled foliations extend from the terminal scrolls h 35 to form the central foliated ornament, and radially-disposed leaves l fill up the space between the scrolls h h and the bold marginal bead d, extending around the upper semicircular end of the handle. 40

On the reverse side of the handle radially-disposed rays form a scalloped segmental crest between the scrolls h and the semicircular upper end of the handle. The lower end of this side of the handle terminates in 45 the foliated ornament m.

Having thus described my invention, what I claim as new, and desire to secure by Letters Patent, is—

The design for the handle of a spoon, fork, 50 or similar article, herein shown and described.

In witness whereof I have hereunto set my hand.

EDWARD W. SCOTT.
